UNITED STATES PATENT OFFICE.

JOHN AREND, OF MANKATO, MINNESOTA.

PISTON-RING.

1,391,816.

Specification of Letters Patent. Patented Sept. 27, 1921.

Application filed July 29, 1920. Serial No. 399,846.

To all whom it may concern:

Be it known that I, JOHN AREND, a citizen of the United States of America, and resident of Mankato, in the county of Blue Earth and State of Minnesota, have invented certain new and useful Improvements in Piston-Rings, of which the following is a specification.

This invention relates to piston or packing rings for internal combustion motors, the said invention having for its object the provision of a sectional packing ring the sections of which are operative to cause close engagement with the walls of the ring groove in piston at the top and bottom of the ring while at the same time it insures a close fit between the piston ring and the cylinder wall; the said invention also having for its object the production of a ring of this character the sections of which are under tension at all times with a force tending to separate the upper and lower ring sections so that there is no liability of the rings becoming bound together or rendered inactive due to deposits of carbon, and the sections of the ring are so operated as to cause them to spread to take up end play or lost motion due to wear.

The main object of this invention is to produce a ring that will automatically adjust itself to the width of the ring groove, if same is worn, and also to prevent any excess oil on the cylinder walls from passing up to the combustion chamber (fouling spark plugs and forming carbon). The lower edge of the upper section of the ring acts as a scraper and on each down stroke of the piston, it fills the cavity with surplus oil and empties it on the up stroke of the piston, leaving a film of oil on the cylinder walls necessary for proper lubrication. The upper edge of the lower section of the ring being cut away allows the oil to pass the lower section of the ring on the up stroke of the piston. The cavity which carries the oil downward is formed by cutting off a portion of the inner and lower section of the ring; therefore, the inner walls of the cavity are not stationary as they would be if cavity were cut in the face of a one-piece ring. Either one of the sections of the ring changing its position by turning in the ring groove would have a tendency to break up any carbon in the cavity and prevent same from baking the ring in the groove. This ring being a combination compression and oil

ring, the use of same would do away with the necessity of using two styles of rings on the same piston. Fewer rings can be used per piston.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a view in elevation partly in section of a piston having piston rings embodying the invention applied thereto;

Fig. 2 illustrates a perspective view collectively of the sections of the ring, and

Fig. 3 illustrates an enlarged detailed sectional view of the ring in its assembled position.

In these drawings, 5 denotes a fragment of a piston, 6 the central section of the piston ring, which, with the companion sections 7 and 8, very nearly fill the groove of the piston ring. The member 6 is a truncated V-shaped member, the base of which lies in close proximity, and in fact, nearly touches or is intended to nearly touch the wall of the groove.

The member 7 has its lower side straight to fit against the groove in the piston, and the upper side is beveled to the contour of the lower edge of the section 6. The edge of the member 7 is beveled or cut away as at 11 with a downward bevel when the piston is operating vertically, the said cutaway portion being intended to produce a clearance for the reception of surplus oil from the cylinder wall while the piston is reciprocating, and this oil is prevented from gaining access to the combustion chamber where it would foul the spark plugs and increase carbon deposits.

The section 8 of the ring has its upper surface or edge straight to fit against the groove in the piston and its lower edge is beveled to the contour of the upper surface of the section 6 of the ring. The upper ring section has its outer face and its lower beveled face intersecting to form an undisturbed edge 13 which acts as a scraper to remove surplus oil which may be present on the walls of the cylinder to which the rings

are applied, whereas there is sufficient clearance between the inner edge of the member 7 and the inner edge of the member 8 to permit the member 6 to act on them to force them outwardly and apart so that they will be in close contact with the walls of the cylinder.

By reason of the cross sectional area of the member 6 which is relatively large, the sections of the ring may be made of cast metal and they need not be made of highly resilient material which so quickly loses its value as a ring producing metal.

The outer edge of the member 6 is well back of the line of contact of the outer surfaces of the members 7 and 8, and the size of the cavity may be increased or diminished according to the amount of material which is removed or admitted from the outer edge 20 of the said member 6, but the proportions shown in Fig. 3 are believed to be illustrative of the most satisfactory means of carrying the invention into practice.

I claim:

25 1. In a piston ring, a series of coacting ring sections comprising a central ring having its top and bottom walls converging outwardly and terminating short of the point of

intersection, an upper ring section having an upper straight side and beveled lower side 30 conforming approximately to the bevel of the central section and having its outer face and beveled edge intersecting to produce an angular lower edge, a lower ring section having a straight lower side and a beveled upper 35 side coacting with the beveled side of the middle section, and having its outer upper edge downwardly beveled.

2. In a piston ring, a central section having converging upper and lower sides terminating short of the point of intersection and having a straight outer wall, a ring section on the side of the central section nearest the combustion chamber of the cylinder to which the piston is applied and having its 45 outer edge remote from the combustion chamber formed at an acute angle and a coacting ring section beveled to the contour of the first mentioned section on the side remote from the combustion chamber, whose 50 beveled edge and cylinder contacting surface are intersected by a beveled portion inclined from the combustion chamber, as and for the purpose described.

JOHN AREND.
